UNITED STATES PATENT OFFICE.

EDWARD S. PILLARD, OF PHILADELPHIA, PENNSYLVANIA.

DOOR FOR SAFES AND VAULTS.

992,981.

Specification of Letters Patent. Patented May 23, 1911.

Application filed September 18, 1907. Serial No. 393,468.

To all whom it may concern:

Be it known that I, EDWARD S. PILLARD, a citizen of the United States, residing at Philadelphia, county of Philadelphia, and 5 State of Pennsylvania, have invented certain new and useful Improvements in Doors for Safes and Vaults, of which the following is a specification.

My invention relates to doors for safes or 10 vaults.

Prior patented vault and safe doors have been provided either with a single outside door, or a double door locked to a central mullion whether the doors have been semi- 15 circular or quadrilateral. It is obvious that any vault or safe door is only as strong as the weakest part and the back bolts on any safe or vault door are placed at that point so that the hinges of the door cannot be removed and the door opened at that point. 20 As the back bolts are only put on such doors for the foregoing purpose, a double door locked to a mullion at the center, is only as strong as its strength at points of locking to 25 the mullion which are the opening points, and consequently, doors of this character are considerably weaker than a single door.

Having the foregoing weaknesses of double, mullion-locked doors in view, the present invention has for its objects, among others, first, to provide a double door for vaults and safes, the respective doors of which are controlled by their separate systems of locks and bolt-work, and hinged in a novel manner so that either may be opened independently of the other and at the outer edge instead of the inner edge and folded or swung back on one another or may be opened or closed as a single door or one opened and 40 swung back on the other and both swung open as a unit; second, to entirely dispense with the mullion heretofore employed and to provide means for the direct engagement of the doors where they meet, thereby making 45 them practically as strong as a single door; third, to provide a novel arrangement of means for drawing the doors closed to effect a very tight fit in the vestibule of the safe or vault which can be operated to tighten or release 50 both doors simultaneously or release one of the doors regardless of whether the other door cannot be opened for any reason.

Among the advantages obtained by the present invention are, first, obviating the necessity of having either a double entrance or an emergency door in the vault; second, re-

ducing the space required in which to swing the door in opening or closing it so that but substantially only one-half the space heretofore required in which to swing a vault or 60 safe door is necessary; third, enabling both doors to be swung as a unit or separately and permitting one of them to be opened as an emergency door if anything is the matter with the other door, thereby preventing a 65 lock-out; fourth, obtaining great strength with simplicity of construction and ease of operation.

I wish it understood that the doors may be of different desired shapes; and that various 70 changes may be resorted to without departing from the spirit and scope of the invention.

The invention is fully set forth hereinafter and its novel features are recited in the 75 appended claims.

In the accompanying drawings:—Figure 1 is a front view showing the doors closed, and Fig. 2, a section on line 2—2 of Fig. 1.

The front wall of a burglar-proof vault is 80 shown at 1 and the double doors 2 and 3 are shown as each constituting a semi-circle, their exterior meeting line being shown at 4. The door jamb may be of the usual stepped construction to prevent the introduction of a 85 liquid explosive, but I have shown it as of the tapered construction commonly employed in vaults made of armor plate. Where the doors abut, they are provided with an interlocking joint 5 extending from 90 top to bottom of the doors. This interlocking joint enables me to dispense with the use of bolts at the meeting faces of the doors and to provide means of many times the resisting power of numerous bolts at this point 95 but in its broad aspect this feature of the invention is set forth and claimed in my application Serial No. 390,733, filed Aug. 30, 1907. The doors may be packed to prevent the introduction of a liquid explosive. 100

Unlike ordinary safe or vault doors which are hinged at their outer edges, the doors of the present invention are hinged at their inner edges to open at their outer edges. Both doors are hung by a single massive hinge 105 which is in the shape of a yoke 6 of sufficient size to permit the doors to be swung through it, this yoke being supported from the front of the vault or safe by the hinges 7. The door 2 is provided with upper and lower 110 hinge members 8, and the door 3 with upper and lower hinge members 9, the latter being

2
received in a slot of the former and hinged thereto by hinge pins or pintles 10 which have a head at one end and adjusting nuts at the other end, ball-bearings 11 being provided to minimize friction.

In order that the parts may be locked together to swing as a unit or to be swung separately, I provide a locking-bolt 20 sliding in keepers 21 and operated by a hand wheel and rack and pinion mechanism 22. When the bolt is shot, the doors are locked together but when retracted, they may be swung independently.

The present invention contemplates the provision of a pressure mechanism which can be operated regardless of position of the doors in relation to each other. On the door 3 there is journaled a shaft 30 which carries a pressure cam 31 at its outer end to engage the pressure fixture 32 on the front of the vault. Journaled on door 2 is a shaft 33 which carries a fixed clutch 34 at one end and at the other end it is connected to the end of shaft 30 by a universal joint 35 and gearing 35^a. Journaled on door 2 is a shaft 33^a which carries a cam 31^a engageable with a pressure fixture 32^a on the front of the vault. The shaft 33^a carries a fixed clutch section 34^a. There is a short shaft 40 which carries sliding clutches 42 and 43, respectively, these clutches being splined to said shaft and adapted to be made to engage the clutches 34^a and 34 by sliding them by hand into engagement therewith. The shaft 40 is revolved by worm-gearing 50 which is operated by a hand wheel 51.

The usual combination lock dials are shown at 60 on the door 2 and at 61 on the door 3 and the handles for operating the bolt-work of the respective doors are shown at 70 and 71.

Carried by the hinge 6 is a sliding spring actuated latch or pin 80 which is adapted to take into an elongated slot 81 in a bracket 45 82 on the door 2. The slot is of sufficient depth to allow the requisite play when the pressure system is operated but causes the door 2 to be engaged with the hinge and to close with it at all times except when the 50 spring latch is retracted, thus facilitating easy closing of the door.

As shown by the various dotted lines and positions, either door may be swung open or closed independently of the other door (the bolt 20 being retracted) or both doors may be swung open as a unit (the bolt 20 being shot). For instance, when the door 3 is swung open and back upon, or substantially so, the door 2, one half of the entrance is 60 open. Thus, if the door 2 cannot be opened for any reason, the door 3 may be used as an emergency door and, similarly, if the door 3 cannot be opened, the door 2 may be opened and used as an emergency door. 65 However the door may be opened by swing-

ing one back upon the other and both swung open together or the doors may be swung open as a unit bodily from the entrance. The yoke like construction of the hinge 6 permits all of these movements and enables 70 the door to be used when there is a limited amount of space available for swinging of the door as it will be seen that only about one-half the usual space is required to swing the doors. In case one door is allowed to 75 remain closed or cannot be opened, the universal joint 35 permits opening of one door without opening the other and thus dispenses with a separate pressure system for each door, while, in case one door is allowed to remain closed or cannot be opened, the clutch (either 42 or 43) controlling the pressure system of that door, is slid by hand out of locked engagement with its companion (34^a or 34), thereby allowing the use of 80 the pressure system on the door which can be swung.

The bolt-work and lock-work may be of any approved construction.

Having thus described my invention, what 90 I claim as new, and desire to secure by Letters Patent, is:—

1. The combination with a single shiftable hinge, of a double door, the members of which are hinged to and bodily movable 95 with said shiftable hinge whereby said door members may be independently opened or independently closed or swung with the hinge as a unit.

2. A double door for safes or vaults, in 100 combination with a single hinge of yoke shape for both of the members of said door, so constructed and arranged that the members of the door are adapted to be swung through said hinge. 105

3. A double door for safes or vaults the members of which are adapted to open at their outermost parts and which have meeting inner edges, in combination with means hinging the door members at their meeting 110 faces so that they may be swung outwardly completely open independently of each other on said inner hinged parts.

4. A double door for safes or vaults the members of which have meeting inner 115 edges, in combination with a single yoke hinge, hinged to the respective door members at their meeting edges above and below them and of greater size than the door members. 120

5. A double door for safes or vaults, in combination with means for hinging the members of said door at their inner parts so that they may be swung independently on said hinge points, and means for locking the 125 door members together so that they may be swung as a unit.

6. The combination with a double vault or safe door, of swinging hinging means to which the members of said double door are 130

hinged so that they may be swung independently of each other, means for securing one of the members of said double door to said hinging means, and means for locking 5 the doors together so that they may swing together as a unit with the hinging means.

7. The combination with a double vault or safe door and means engaging the members thereof so that they may be swung independently of each other or together, of a 10 pressure system comprising pressure devices carried by the respective members of the door connected together for operation regardless of the respective positions of the 15 members of said door, and means for operating said pressure system.

8. The combination with a double vault or safe door and means engaging the members thereof so that they may be swung independently of each other or together, of a 20 pressure system comprising pressure devices carried by the respective members of the door connected together for operation regardless of the respective positions of the 25 members of said door, means for operating said pressure system and means for render-

ing inactive either part of the pressure system without interfering with the operation of the other part thereof.

9. The combination with a double door 30 for safes or vaults, of means hinging the inner members of said door so that they may be swung independently of each other, and a pressure system comprising means on the respective door members, a universal 35 joint connecting the pressure means of one door member with that of the other door member, operating means on one of the door members, and clutches controlling the operation of the respective parts of the pressure 40 system whereby the pressure means of one door member may be operated independently of that of the other door member and regardless of the positions of the door members. 45

In testimony whereof, I hereunto affix my signature in presence of two witnesses.

EDWARD S. PILLARD.
